TYPE COMPOSING MACHINE

Frank H. Poeppelmeier, Dayton, Ohio, assignor
to Dayton Type, Incorporated, a corporation
of Delaware

Application April 12, 1937, Serial No. 136,244

21 Claims. (Cl. 276—18)

This invention relates to new and useful improvements in type composing machines.

It is one of the principal objects of this invention to provide a typesetting machine which is not only highly efficient, but performs the tasks expected of it at reasonable cost. Many parts and sub-assemblies required in other models have been eliminated, making my improved machine simple in design and economical to produce.

My invention contemplates a single, wide conveyor belt which carries the type to an ejector by which it is discharged in a properly timed manner to a printing segment, chase plate or individual channels.

The magazines holding the type are located above the continuously moving belt at one end of the machine. The upper and lower case magazines are in this instance set directly opposite each other in the form of a V or spear head, with the point of the V projecting toward the end of the machine.

The type is placed in the magazines so that the foot of the type faces toward the ejector end of the machine. Through the operation of a keyboard, where electrical contacts are made and broken, a solenoid is actuated each time a key is depressed and the character in the magazine corresponding to the depressed key is ejected from the magazine in the same direction the belt is traveling and onto the belt.

Two guide rails converge over the wide conveyor belt to sweep the type discharged upon it into a channel formed by those rails to guide that type to a horizontal disc at the opposite end of the machine. These guide rails are set at the most effective angle to keep the type from spinning around or partially turning when the type traveling on the belt toward the rails finally contact the latter for guidance by them the remainder of the way to the fixed channel which they form.

The purpose of setting the magazines at an angle and not straight across the belt, is to compensate for the greater distance that the type located away from the center of the belt must travel, than the shorter distance traveled by the type located near the center of the belt, to the opening and fixed channel formed by the guide rails. Also, the magazines are set at an angle instead of straight across the belt to compensate for the friction set up by both the belt and guide rails when a piece of type is carried down and across the belt at the same time. The angular setting of the magazines, therefore, is to

prevent transposition of characters which would occur if the magazines were set directly across the belt.

The disc which receives the type from the belt is traveling in the same direction as the belt. The type is carried on the surface of the disc and held in its course by a fixed channel. The disc is equipped with a set of three timing blades which controls the type to the extent that only one piece of type at a time is presented to the ejector at the exact time the ejector blade is in a position to accept the single piece of type and eject it into the printing segment.

The reason for projecting the type foot first from the magazine onto the belt is because, regardless of the character on the type body, the feet of all pieces of type are identical. This permits the machine to be equipped with a pocket of a design to guide the type into this pocket where it settles and is held until the ejector blade picks it up and transfers it to the printing segment.

By having the type channels of the magazines one beside the other, there is provided an easy and visual inspection of the type remaining in the magazine, thus eliminating mechanical warning devices that the channels are empty.

Also, the magazine channels are so constructed that when very thin pieces of type are loaded into the channels, a guide plate can be inserted into the channel and the entire tube of thin type carried down to the bottom (much as an elevator descends with its load), after which the guide plate is removed. This eliminates the possibility of the thin type turning around in the channel due to the very thin dimensions of the type body. By thin type is meant gothic "i," "l," etc.

Other important and incidental objects will be brought out in the following specification and particularly set forth in the subjoined claims.

In the accompanying drawings illustrating one form of embodiment of my invention, Figure 1 is a front view of my wide belt type composing machine. Figure 2 is a top plan view of the same. Figure 3 is a detail sectional view taken through one of the magazines, showing how the type are mounted with their feet foremost with respect to the direction of the feed of the conveyor. Figure 4 is a longitudinal sectional view taken through the magazine end of the machine. Figure 5 is a perspective view of one of the type ejecting shuttles. Figure 6 is a perspective view of one of the shuttle guides. Figure 7 is a sectional view taken through one of the shuttle and guide assemblies. Figure 8 is a side view of one

of the solenoid contact-leaf assemblies. Figure 9 is a transverse sectional view taken through the type-composing keyboard. Figure 10 is a sectional view taken through one of the character-key switch assemblies. Figure 11 is a sectional view taken through one of the shift-key switch assemblies. Figure 12 is a sectional view taken through one of the switch controls for the magazine spacer-slug channels. Figure 13 is an electric circuit diagram. Figure 14 is front view of the type ejector mechanism. Figure 15 is a side view of said mechanism, with the ejector casing shown in its open position to disclose the means for conducting the type therethrough from the timing mechanism to the printing segment. And Figure 16 is a top plan view of the timing and ejecting mechanisms.

Referring to the accompanying drawings for a detailed description of my invention, the numeral 1 designates a rectangular supporting frame mounted on legs 2. This frame is covered with a metal siding 3 which, at the front, is formed with a wide, tapering opening 4 below an outwardly projecting keyboard 5 carried by the frame.

Transversely mounted in the top portion of the frame 1 at one end thereof, is a roller 6 over which a single, wide fabric belt 7 is movable. This belt, whose upper run constitutes a flat top 30 for the frame, passes around two rollers 8 and 9 mounted one above the other at the other end of the frame. Of a width which is substantially that defined by the space between the sides of the frame, the belt 7 is moved clockwise by the roller 6 to convey toward the latter any type which is discharged upon it at the double roller end of the machine.

For the purpose of discharging type feet first upon the wide belt 7 there are mounted on the double roller end of the frame 1, magazines 10 and 10^a later to be described; and to receive this type from the belt at the opposite end of the machine an ejector 11 is secured to the front side of the frame. After the type falls from the magazine upon the belt, it is guided to the ejector by two rails 12 and 13. These rails, which are secured to the top members of the frame 1, converge over the belt in front of the magazines to form a narrow channel 14 that leads to the ejector. This type which is discharged upon the belt 7 between the outwardly flaring ends of the rails, will be directed inwardly by them into the channel 14, through which they are carried single file, feet first, to the ejector 11 by the belt. Glass plates 12^a and 13^a, whose inner sides are flush with the inner sides of the rails 13 and 14 respectively, cover the belt 7 beyond the rails.

The belt 7 is rotated, and the ejector 11 is actuated, by a motor such as the electric motor 15. The latter is mounted on the frame 1 in front, and at one side, of a pulley 16 carried by a countershaft 17 journaled in a gear reduction casting 18 secured to a bottom member 19 of the frame. The pulley 16 is driven by a belt 20 from a pulley 21 on the armature shaft of the electric motor. (See Figures 1 and 2).

The countershaft 17 carries on one end a fixed pinion 22 which meshes with a gear 23 secured to a shaft 24 also journaled in the casting 18. Also secured to the shaft 24 is a pulley 25 that drives a pulley 26 on a shaft carrying the roller 6, through a belt 27. Through the reduction gearing just described, the belt is driven at mod-

erate speed by the fast rotating motor 15. (See Figure 1).

The wide belt 7 is tightened or relaxed by adjusting the vertical position of the rear roller 9 with respect to the upper roller 8. The shaft 28 upon which the roller 8 is mounted, is fitted at its ends within recesses 29 in castings 30, 30 secured to angle irons 31 on the frame 1. By means of screws 32 which engage it from above, the shaft 28 is held in the recesses of the fixed castings 30, 30. (See Figure 4).

The lower roller 9 is mounted on a shaft 33 whose ends float in vertical grooves 34 in the portions of the castings 30 which project below the angle irons 31. The position of the shaft 33 is adjusted by screws 35 which pass downwardly through tapped holes 36 in the castings, into engagement with the ends of the shaft. When the screws are forced downwardly, they will press upon the ends of the shaft 33 to hold its roller 9 in tight contact with the belt 7 which passes over it, thereby giving it the desired tautness to carry type from the magazines 10 and 10^a now to be described to the ejector 11. (See Figure 4).

Each type magazine comprises a rectangular frame including two upright end members 37, 37 and top, bottom and intermediate ribs 38. Extending the length of the frame, and brazed in the ribs 38, are vertical channel strips 39 spaced a proper distance apart. Each channel strip 39 is machined to provide in each front side a U-shaped type receiving channel 40. The channel 40 on one strip forms with the channel 40 in the adjacent strip a split tube to receive the type flatwise, with their feet pointing in the direction of their discharge upon the belt 7. (See Figures 2, 3, and 4).

The type magazines, in this instance two, the upper case type magazine 10 and the lower case type magazine 10^a, are mounted in staggered relation upon the top of the frame 1, the end members 37, 37 of each magazine frame resting upon an inclined member 41 supported at its ends upon the side members of the frame 1. Mounted in front of each magazine on an end bar 42 connected to a respective inclined member 41, is a plate 43 grooved to receive type discharged from the bottoms of the channels in its respective magazine. The two plates 43, 43 are connected together in this instance by a bridge bar 44. (See Figure 2).

The column of type in each channel rests upon a cross plate 45 which projects beneath the shuttle-retaining casting 46 for attachment thereto. This plate 45, which projects outwardly below the type channels, extends the entire length of its magazine frame to support the lowermost type in a position to be ejected by shuttles 47 upon the belt 7 which runs about ten thousandths of an inch below the plate. (See Figure 4).

The shuttle assembly for ejecting the lowermost type, one at a time, feet first from each magazine will now be described. Secured by screws 48 to the lower rib 38 of each magazine is the shuttle-retaining casting 46 having a rearwardly projecting foot portion 49. Longitudinally insertable in grooves in the bottom of the casting 46 are U-shaped shuttle guides 50 that are held in place by wires 51 and 52. The backs of the channel strips 39 of each magazine fit against the wire 51 and a plate 54 bears against the wire 52 to hold them in place. Movable in the shuttle guides 50 are the shuttles 47 adapted to engage respective type and force them feet

first from the lower portions of the magazines onto the belt 7. (See Figures 4, 5, 6, and 7).

Each shuttle 47 is an elongated metal member formed with a reduced type engaging end, and having a middle slot 55 in its top portion and an elongated slot 56 in its rear top surface. (See Figure 5).

For the purpose of holding each shuttle 47 in a normal position behind its respective type in the magazine, is a retaining pin 51 having a double V-shaped upper end which projects through a hole in a fulcrum bracket 58 secured by a screw 59 to the casting 46. Attached to the lower V-portion of the retaining pin 51 is a tension spring 60 that is secured at its outer end to an anchor piece 61 attached by a screw 62 to the foot portion of the casting 46. Also attached to the latter by the screws 62 is the plate 54 whose lower end enters the slots 56 in the shuttles 47 to limit their rearward and forward movement. The front and rear sides of the guides 50 are formed with recesses 63 to receive the wires 51 and 52 by which these guides are bound together in an assembled unit. (See Figures 4, 5, 6, and 7).

For the purpose of engaging each shuttle 47 to force it inwardly to eject a lower type from its respective magazine channel, is a shuttle bar 64. These shuttle bars 64 are slidably mounted in grooves in a shuttle-case casting 65. Retaining plates 65^a are applied to the casting 65, which, with the shuttle assembly and plates, is removably secured to the frame 1 so that the whole unit may be easily removed to insert or remove the shuttle bars.

Each shuttle bar 64 has a downwardly turned rear end 66 which engages in a notch 67 in the head 68 of a shuttle crank 69 pivotally secured by a pin 70 to a transverse supporting member 71 secured between the castings 30, 30. This member 71 is formed with slots to receive the pivoted ends of the cranks 69 in spaced relation. Connected between each crank 69 and an anchor piece 72 on the lower end of the casting 65, is a coil spring 73. Attached to an angle iron 74 at the rear end of the frame 1 is a guide bracket 75 for the outer ends of the cranks. (See Figure 4).

Secured to angle irons 76 and 77 of the frame 50 1 is an inclined wood member 78 to which is attached a bracket 79 terminating at its ends in guide flanges 80 and 81. On the lower side of each crank 69 is a pad 82 adapted to be engaged by a push rod 83 which passes through holes in 55 the guide flanges 80 and 81 of the bracket member 79. (See Figure 4).

Each rod 83 is adapted to be raised by a plunger 84 in a solenoid cylinder 85. These solenoid cylinders 85 are mounted in a casing 86 having on its rear portion a boss 87 that terminates below the casing in forked extensions 88. These extensions 88 straddle pins 89 on a supporting block 90 secured to the member 79. Formed on the upper portions of the boss 87 is 65 a pad 91 which braces the solenoid casing against the member 78 and is secured thereto by screws 92. Secured to the solenoid case is a U-shaped bottom 92^a carrying a resilient pad 92^b upon which the lower ends of the plunger 84 normally rest.

One end of each solenoid winding 93 leads to a screw 94 on each side of the solenoid casing 86, while the other end 95 of each solenoid winding leads to a screw 96 adjacent the screw 94 on each side of the solenoid casing. The screws 94 are

engaged by leaf contacts 97 secured by screws 98 to fiber boards 99, 99 attached to the sides of the solenoid case. From each screw 98 a wire 100 leads to the individual key on the keyboard corresponding to that screw.

Engaging the screws 96, which are on the solenoid casing sides in staggered relation with the screws 98, are leaf contacts 101 that are secured to screws 102 on the fiber boards or bars 99, 99. On each of these fiber boards the leaf contacts 10 101 and 101 are alternately arranged, the contacts 97 being included in the individual key circuits, while the contacts 101 are common. The screws 98 are common, in that wires do not lead from them to the individual keys, but instead there are connected to these screws wires 15 103 that lead to the common source of current supply. (See Figures 4 and 8.)

When it is desired to remove the solenoid case, the wiring need not be disturbed, since the fiber 20 boards 99, 99 may be first taken off, whereupon it and the wires connected thereto will be left dangling while the solenoid case itself is removed.

Each time a solenoid 85 is energized by the closing of a key circuit soon to be described, its 25 plunger 84 will be raised to force its respective push rod 83 upwardly into violent contact with its respective crank 69. The latter in turn will be rotated to move the shuttle bar 64 inwardly to engage and force in the same direction its respective shuttle 47 to eject from the magazine a type corresponding to the key depressed on the keyboard. (See Figure 4).

The keyboard 5 consists of a subframe 104 having a base portion 105 integral with a perpendicular back 106. At each side of the base portion 105 there is an inclined end 107 whose sloping surface is formed with spaced, transverse square recesses 108. Mounted in these recesses in the ends 107 of the keyboard are transverse 30 40 mounting bars 109 arranged in parallelism and constructed of a non-conducting material such as Bakelite, vulcanite or hard fiber. (See Figures 9, 10, and 11).

Positioned above the subframe is a key frame 45 110 whose upper face 111 is formed with a series of stepped bosses 112 extending transversely of the key frame. At its sides this frame has flanges 113, 113 that extend downwardly to the base portion of the subframe 104 to completely enclose 50 55 the space beneath it.

Each of the bosses 112 is provided with a series of holes 114 perpendicular to the boss face and spaced laterally in conformity with standard typewriter keyboard spacing. In the upper boss 55 112^a there are two holes 114, 114 to receive the stem projections 115 of auxiliary keys 116. In each of the intermediate bosses 112^b, 112^c, 112^d and 112^e, I have provided a series of spaced holes 114 to receive the stems 115 of case letters and 60 numerals combined with the usual characters. In the lower boss 112^f I have provided two holes 114, 114 to receive the stem projections 115 for a second spacer bar 118. (See Figure 9).

Positioned below the lower spacer bar 118 are 65 three contact blades 119, 120, 121 supported in the bars 109 with the free ends of the blades 119 and 120 in contact and the blades 120 and 121 in spaced relation to each other. Now, when the spacer bar 118 is depressed, its stem 115 will 70 open the circuit including the blades 119 and 120 and engage the latter blade with the blade 121 to close the electric circuit including the spacer solenoid 85 to cause the latter to actuate the 75

shuttle 47 which discharges a spaced lug from the magazine channel containing it.

Positioned below each of the keys 116 and 117 for the upper and lower case letters and those 5 having two characters thereon, are triple contact blades 122, 123, 124, as shown in Figure 10, and actuated by the stems 115 of their respective keys 116 or 117. As shown in Figure 10, the blades 122, 123 and 124 are mounted in a super- 10 imposed position supported by the bars 109 and with their free contact ends in spaced relation to provide open circuits between them. When one of these keys is depressed its stem will press the blade 123 into engagement with the blade 124 to form an electric circuit through the solenoid 85 corresponding to that key, whereupon the shuttle 47 operated by that solenoid will eject from the magazine the upper or lower case type belonging to that key.

20 To set the electric mechanism for the delivery of a lower or an upper case character type, shift keys 125 are provided. There are two of these shift keys 125, one located at one end and the other at the opposite end of an intermediate key- 25 bank. Positioned below the stem 115 of each shift key is a series of three contact blades 126, 127 and 128 supported in a bar 109 and having their free outer ends below the key stems. Normally the center blade 127, which is actuated 30 by the stem 115, is in contact with the upper blade 126, to maintain an electric circuit through the lower case solenoids, but when the key is depressed, this circuit is opened and a new circuit, including the upper case solenoids, is formed between the center blade 127 and the lower blade 128. When the shift key is released the original 35 circuit is re-established. (See Figure 11).

Referring now to the complete circuit diagram as shown in Figure 13, alternating line current 40 of 220 volts is carried by the conductors 129 and 130 to the primary 131 of a step down transformer. From the secondary winding 132 current at 110 volts is impressed upon the mains 133 and 134. In case 110 volt current is available, it is impressed directly upon the mains 133 and the transformer is omitted.

50 In the main 134 is a line fuse 135, and a single pole switch 136 having a control handle 136a that projects from the front of the frame 1 between the keyboard 5 and the ejector 11. From one side of this switch current is delivered through a lead 137 to the motor 15 whose opposite side is connected through a lead 139 with the main 133.

55 Also connected to the lead 137 is the lead 140 to the contact blade 127 of the shift keys 125. From the blade 126 the common lead 103 connects with one side of the lower case letter solenoids 142 and spacer solenoids 143 grouped there- 60 with. Connected with the blade 128 is a common lead 144 that connects with one side of the capital letter solenoids 145 and spacer solenoids 146 grouped therewith.

65 From the opposite side of the solenoid windings of each of the lower case letters the lead 100 connects with the center blades 123 of their respective keys 117. From the opposite side of the solenoid windings for each of the capital letters, a lead 147 connects with the upper blade 122 70 of its respective key 117.

The opposite side of the solenoid windings of each spacer bar is connected through a lead 148 with one blade of its respective spacer bar switch 149. These switches 149, one for each spacer 75 solenoid, are provided for dual magazines of spacers

ers and as the supply of spacers in one magazine is depleted, its solenoid circuit will be opened and the other spacer magazine solenoid closed, manually, to provide a sufficient supply of spacers for the type composition.

5 The opposite side of the switches 149 for the spacer solenoids in the capital letter magazine are connected through a common lead 150 with the top blade 119 of the spacer switch and the opposite side of the switches 149 for the spacer 10 solenoids in the lower case letter magazine are connected through a common lead 151 with the center blade 120 of the spacer switch. The lower blade 121 is connected through a lead 152 with the keyboard common lead 153. In series with the 15 junction of the leads 152 and 153 and the opposite main lead 133 to which they are connected, is a resistor 154. This resistor is omitted, however, on all common voltages except 220 volts, direct current. When direct current is used I employ 20 a condenser 155 connected between the leads 137 and 153, to reduce arcing at the various contacts.

For the purpose of operating the switches 149 to open one spacer magazine channel and then the other, I have provided in each side 113 of the 25 keyboard 5 a hole which receives a shaft 156 carrying on its outer end a knurled thumb screw 157. (See Figure 12). One of these switches controls two spacer channels in the lower case magazine and the other switch controls two spacer channels in the upper case magazine. Pinned to the inner end of the shaft 156 is a collar 158 carrying a horizontal switch member 159 made of Bakelite or other suitable insulating material, to engage and spread apart the contact blades on 30 one side of a switch 149 and permit the blades on the other side of that switch to engage each other to close the circuit through the solenoid corresponding to the filled spacer magazine channel.

40 After the type is discharged upon the belt 7 by the key-controlled mechanism just described, it is carried by that belt to the ejector 11, which will now be described. Secured to the left-corner side of the frame 1, where the type leaves 45 the outer end of the channel 14, is an ejector casing 160. A bracket arm 161, the upper portion of which forms one support for the ejector casing, has a lower straight part which is attached to the front portion of the frame 1.

50 Secured to the upper end of the bracket arm 161 is an apron 162 that is supported at its outer end by the upper end of a bracket 163 that is attached to a corner member 164 of the frame 1. Behind a chase or printing segment 165 carried by the apron 162 there is secured to the frame 1 a horizontal outwardly projecting member 166 having an upwardly projecting boss 167. Secured to this boss is a vertical shaft 168.

55 Freely rotatable upon the boss 167 around the stationary shaft 168 is a worm gear 169, to which is attached, by means of a projection 170 that enters a slot in the upper face of the gear, a sleeve 171 which flares outwardly at its top portion to support a rotatable disc 172. This disc is 60 so located that type will be discharged upon its upper surface by the belt 7 from the mouth of the channel 14. The disc 172 is rotated by the worm gear 169 which meshes with a worm wheel 173 mounted on a shaft 174 journaled in the 65 ejector support. The gear 173 in turn meshes with a worm 175 on a shaft 176 journaled in the frame 1. To the opposite end of this shaft a pulley 177 is secured to receive a belt 178 which passes around a pulley 179 on the countershaft 70 75

24 for rotation by the motor 15. (See Figures 14, 15, and 16).

Attached to the top of the frame 1 over the rotating disc 172 is a cover plate 180 having an outer surface which forms a curved continuation of the channel edge of the cover plate 12^a. Attached to the cover plate 180 by bridge bars 181 and 182 is a timing finger plate 183 whose inner side is curved similarly to the curved surface of the cover plate 180 to form therewith a channel 184 through which the type passes one at a time to an ejector cam 185 mounted on a shaft 186. This shaft, which is journaled in the ejector casing, has mounted on its inner end a worm gear 187 that meshes with the worm 188 on the shaft 174 for rotation at reduced speed by the motor 15 through the belt pulley and gear connection heretofore described.

The timer to which the type is carried by the disc 172 through the channel 184 will now be described. Formed in the upper surface of the plate 183 at right angles to the channel 184 are three grooves in which three timing fingers 189, 190 and 191 are movable. These fingers are held in the grooves by a cover plate 192 secured to the timing finger plate. Each one of these timing fingers has a beveled outer end which is adapted to project into the channel 184 to momentarily intercept the passage of type therethrough for timing purposes. Each timing finger has an upturned rear end that is adapted to be engaged by a cam rod 193 which projects through a hole in a vertical flange 192^a on the cover plate 192 and a hole in the vertical flange 194 on an angle plate 195 secured to the cover plate 180. Attached to the top portion of the angle plate 195 are the hook ends of three tension springs 196 whose outer ends are hooked to the upturned rear ends of the timing fingers to draw their front ends a sufficient distance into the channel 184 to prevent the passage of type therethrough.

The timing fingers 189, 190 and 191 are forced outwardly by the following means to clear the channel 184 for the passage of type therethrough. Adjustably secured to the top face of the disc 172 below a nut 197 secured to the stationary shaft 168 is a sleeve cam 198. This cam has formed on its periphery three superimposed sets of four lobes 199, one set for each cam rod 193. The cam rod holes in the flange on the angle plate 195 are so disposed that the cam rod 193 for each timing finger will engage a respective set of lobes on the sleeve cam 198. The lobes of each set are ninety degrees apart, with the lobes of the first and third sets being in alignment, while the lobes of the middle set are midway between the lobes of the first and third sets. The lobes 199 are arranged in this manner so that they will alternately engage the inner ends of the cam rods 193 to force them outwardly a sufficient distance to remove their respective timing fingers from the channel 184 against the tension of their respective springs 196.

When the disc 172 is rotated to carry a type through the channel 184, that type will be first intercepted by the beveled end of the timing finger 189. This finger will restrain the movement of that type through the channel 184 until the finger is forced outwardly by its respective cam rod 193 when actuated by a lobe 199 on the sleeve cam 198. The outward movement of the first finger 189 is timed to begin as the second timing finger 190 is in position within the channel 184 to intercept the passage therethrough of the type to be released by the first finger. The sec-

ond finger 190 will then hold the type until that finger is forced from the channel 184 by its respective lobe-actuated cam rod 193. When this occurs the tension springs 196 attached to the first and third fingers 189 and 191 will draw these fingers inwardly to project their beveled ends in unison into the channel 184. The third finger 191 then intercepts the type released by the second finger 190 while the next or second type engages the first finger 189. Then, when the first and third fingers are forced outwardly by their respective cam rods 193 the second type will engage the second finger 190 now drawn into the channel by its spring 196 and the first type will enter the ejector.

It is thus seen that my timing mechanism releases one type at a time to the ejector. Three timing fingers are provided so that if a type should miss the first finger 189 it will be intercepted by either the second finger 190, or the third finger 191 for proper release thereby to the ejector mechanism now to be described.

The ejector casing into which the type, after passing the timing fingers, is carried by the disc 172, will now be described. Referring to Figures 14, 15, and 16 the numeral 200 designates a vertical wall plate that is fixedly attached to the ejector casting. This plate is formed with a radial notch 201 into which the disc 172 projects. Just below this notch there is formed on the inner surface of the plate a flat boss 202 having a curved upper edge to receive feet first from the disc 172, the type which have passed the timing fingers.

Also formed on the inner surface of the plate 1, above the ledge boss 202 is an integral guide rib or rail 203 which has a curved portion that comes to a point 204 just above the ledge to receive the type placed foot first upon the latter by the disc 172. From its curved end portion the rib 203 continues in a straight line to the side of the plate opposite the printing segment 165.

Through a central hole in the plate 200 the end of the shaft 186 projects to receive the vertical cam disc 185. The latter is pinned to the shaft to be rotated thereby to bring its lobes 205, in this instance eight, past the ledge 202 to pick up the type thereon and place it on the guide rail 203.

Hingedly secured to the lower portion of the fixed plate 1 is the upper edge part of the cover plate 206. The latter carries a forked locking piece 207 adapted to receive a drop bolt clamp 208 hingedly secured to the top of the plate 200 to lock the cover plate 206 in a vertical position against it.

The cover plate 206 has formed on its inner surface a boss 207^a shaped similarly to the ledge boss 202 on the plate 200 and forms with the latter, when the plate 206 is locked against it, a double ledge upon whose upper curved peripheries a type is placed foot first by the disc 172. (See Figure 15.)

The cover plate 4 also has formed on its inner surface a rib or rail 208^a similar to the rib 203 and forming therewith a channel through which the lobes 205 on the disc cam 185 travel when the latter is rotated. These two rails 203 and 208^a form together a track to which a type is carried from the ledge 202—207^a. This type is so presented to the track that the grooves in the type will fit the rails, with its head resting upon their top surfaces and its foot below them. Thus supported, the type is forced between the rails 70

203—208^a by a lobe of the cam to a type-receiving channel in the chase 165. It is thus seen that after the type is deposited foot first upon the ledge 202—207^a by the disc 172, it will be engaged by a lobe 205 of the vertical cam disc 185 and forced between the guide rails 203—208^a to the type channel on the printing segment 165 in position to receive it.

In operation, printer's type as well as any other short type bearing upper and lower case characters are inserted in the split tubes of the magazines 10 and 10^a. Preferably, type carrying the lower case characters are inserted in the magazine 10, and type bearing the upper case characters are placed in the magazine 10^a.

The switch 136 is then actuated to close the motor circuit to start the movement of the conveyor belt 7 and the receiving disc 172, and the operation of the timing and ejecting mechanisms.

20 If the first sentence of the composition to be set up on the chase 165 is started with a capital letter, or any other upper case character, the operator depresses the shift key 125 on the right or left side of the machine. The depression of this key moves the middle contact blade 127 away from the contact blade 126 to open the circuit which includes the lower case solenoids, and into engagement with the lower contact blade 128 to form an electric circuit through the upper case 25 solenoids. (See the wiring diagram in Figure 13).

A key 117 displaying the character desired is now depressed by the operator to engage the middle contact blade 123 with the contact blade 124. 30 This closes an electric circuit through the solenoid 85 corresponding to the depressed key. When this solenoid is energized, its respective plunger 84 will be forced upwardly to raise its push rod 83 and through it, turn its respective crank 68 to press inwardly a shuttle bar 64 that actuates a shuttle 47 to eject from the magazine an upper case type corresponding to the key depressed. This type falls foot first upon the wide belt 7 by which it is carried through the channel 14 to 35 the surface of the disc 172. The latter, which is traveling in the same direction as the belt, carries the type through the channel 184 past the timing fingers 189, 190 and 191 to the ejector 11. The type, still traveling foot first, is deposited 40 by the disc 172 on the ledge 202 in the ejector casing, where it is picked up by the ejector disc cam 185 and forced along the track 203—208^a onto the printing segment 165.

If the next letter of the word is a lower case 45 one, the operator releases the shift key 125, which permits the middle contact blade 127 to spring back into engagement with the upper contact blade 126 to re-establish the circuit that includes the lower case solenoids. The key 117 for the desired 50 lower case letter is now depressed to bring its contact blades 123 and 124 into engagement to close the electric circuit including the lower case solenoid 85 corresponding to that key. Through its push rod, crank and shuttle bar, the shuttle 55 47 corresponding to that key will then be forced outwardly to eject a type corresponding to that key upon the belt 7 to follow quickly the upper case type previously ejected, through the channels 14 and 184, and the ejector casing, into the printing segment. After a word has been formed 60 by the type ejected by the depressed keys 117, a spaced bar 118 is actuated. The stem of this bar then presses the contact blade 120 into engagement with the contact blade 121 below it to close 65 an electric circuit through the solenoid for the 70

magazine channel containing a spacer slug. This slug will then be ejected by the solenoid-actuated shuttle 47 upon the belt 7 for carriage by the belt, disc 172 and ejector disc cam 185 to the printing segment 165, where it rests behind the last type placed therein by the same means. In this manner the complete copy on the printing segment is formed.

It is thus seen that my improved type-composing machine performs the task of setting up the 10 copy on the printing segment, quickly, accurately and efficiently. Many parts and sub-assemblies heretofore required are eliminated, making the present machine simple in design and economical to produce. 15

Having described my invention, I claim:

1. In a type composing machine, a type magazine, an ejector, a wide belt passing below the magazine to receive the type discharged therefrom and to conduct it to the ejector, and means 20 for discharging type feet first from the magazine upon the belt for carriage by the latter to the ejector.

2. In a type composing machine, type magazines set at an angle to each other at one end 25 of the machine, an ejector at the other end of the machine, a wide belt passing below the magazines to the ejector, and means for discharging type feet first from the magazines upon the belt for carriage by the latter to the ejector. 30

3. In a type composing machine, a keyboard, a magazine containing a type channel for each key on said board, means operated by said keys for ejecting type from said magazine, two spacing slug channels in said magazine, means for ejecting slugs from one or the other channel, a solenoid for operating each slug ejecting means, an electric circuit including each solenoid to energize the same, and a switch in the keyboard to close the electric circuit through the selected 40 solenoid to discharge slugs from its magazine channel until empty, after which said switch may be actuated to open said circuit and close the circuit through the solenoid for the filled slug magazine. 45

4. A type composing machine comprising a keyboard, a magazine containing a type channel for each key on said board, means operated by said keys for ejecting type from said magazine, two spacing-slug channels in said magazine, means 50 for ejecting slugs from one or the other channel, a solenoid for operating each slug-ejecting means, an electric circuit including each solenoid to energize the same, and a switch in the keyboard to close the electric circuit through the selected 55 slug solenoid, and to open that circuit when the magazine channel for that solenoid is empty and at the same time to close the circuit including the solenoid for the filled slug magazine.

5. In a type composing machine, a type magazine, shuttles for discharging type from said magazine, a solenoid case, solenoids in said case, plungers in said solenoids, a keyboard, keys on the latter, circuit closing and opening means adapted to be actuated by said keys when depressed, an 60 electric circuit including each key-circuit closing and opening means with a respective solenoid, and crank and rod actuating means between each solenoid plunger and its respective shuttle. 65

6. A solenoid support for a type composing machine, including a solenoid case, a bracket for holding said case, solenoids in said case, contact screws on one side of said case, wiring connected between said solenoids and said screws, an insulating bar removably secured to the same side of 70 75

the case as the screws, wiring secured to said insulating bar, and leaf contacts on said bar connected with the latter wiring and having a free engagement with the heads of said screws to complete a circuit between the latter wiring and the solenoids, said leaf contacts permitting the easy removal of the bar from the solenoid case, and the consequent removal of said case from the bracket without disturbing the wiring connected to said bar.

7. In a type composing machine, a type magazine, vertical type-containing channels in said magazine, an ejector casing secured to the back of said magazine, said ejector casing formed with horizontal slots in its bottom portion, guides mounted in said slots, shuttles movable in said guides to engage and force type from the bottom of said magazine channels, a keyboard, and means actuated by the keys therein for shifting the shuttles corresponding to said keys to discharge respective type from the magazine channels when said keys are depressed.

8. In a type composing machine, a type magazine, vertical type-containing channels in said magazine, an ejector casing secured to the back of said magazine, said ejector casing formed with horizontal slots in its bottom portion, U-shaped guides having their sides mounted adjacent each other in said slots, shuttles movable in the bottom portions of said guides, and formed with slots in their upper portions, retaining pins hingedly mounted in said casing, with their lower ends in the slots in the shuttles, anchored springs normally restraining the outward movement of the shuttle-engaging ends of said rods, a keyboard, and means actuated by the keys therein for forcing the shuttles corresponding to said keys outwardly to discharge respective type from the magazine channels when said keys are depressed.

40 9. A shuttle case attachable to the back of a type-containing magazine, comprising a vertical portion and a rearwardly extending foot portion, said case formed with horizontal slots in its bottom portion, U-shaped guides having their sides mounted adjacent each other in said slots, said guides formed with slots in their front and rear upper ends, wires fitted in said slots to hold the guides in said case, and shuttles movable in said guides below said wires to eject type from said magazine.

50 10. A shuttle case attachable to the back of a type-containing magazine, comprising a vertical portion and a rearwardly-extending foot portion, said case formed with horizontal slots in its bottom portion, U-shaped guides having their sides mounted adjacent each other in said slots, said guides formed with slots in their front and rear upper ends, wires fitted in said slots to hold the guides in said case, shuttles movable in said guides below said wires, said case formed with a middle opening, retaining rods in said opening hingedly secured to the upper part of the vertical portion of said case, with the lower ends of said rods in engagement with said shuttles, anchor pieces secured to the foot portion of said case, tension springs connected between said anchor pieces and said retaining rods, said shuttles formed with slots in their rear top portions, and stop plates secured to the foot portion of said case to engage in said shuttle slots and also to hold the rear wires in their respective slots in the guides.

70 11. In a type composing machine, a type magazine, an ejector, means for delivering type from the magazine to the ejector, a plurality of timing

5 fingers movable into the path of forward movement of the type to permit the presentation of one type at a time to the ejector, a vertical cam cylinder formed with superimposed sets of lobes on its periphery, and means adapted to be engaged by said lobes to actuate the timing fingers.

12. In a type composing machine, a type magazine, an ejector, means for delivering type from the magazine to the ejector, a plurality of timing fingers movable into the path of forward movement of said type to permit the presentation of one type at a time to the ejector, a vertical cam cylinder formed with superimposed sets of lobes on its periphery, springs for normally holding the timing fingers in the path of forward movement 15 of the type, and means adapted to be engaged by the cam lobes to force said fingers out of the path of forward movement of said type.

13. In a type composing machine, a type magazine, an ejector, means including a horizontal disc 20 for carrying type from the magazine to the ejector, a plurality of timing fingers movable over the disc for engagement with the type to permit the presentation of one type at a time by the disc to the ejector, a sleeve cam secured to the disc and formed with superimposed sets of lobes on its vertical periphery, springs for normally holding said fingers in the path of movement of the type toward the ejector, and means adapted to be engaged by the sleeve cam lobes to force said 25 fingers alternately out of the path of forward movement of said type.

14. In a type composing machine, a magazine, an ejector, means including a horizontal disc for carrying type from the magazine to the ejector, 30 a plurality of timing fingers movable over the disc for engagement with the type to permit the presentation of one type at a time by the disc to the ejector, a sleeve cam secured to the disc and formed with superimposed sets of lobes on 35 its vertical periphery, guide means, cam rods movable, one above the other, through said guide means for engagement with respective sets of cam lobes, the rear ends of said rods adapted to contact the timing fingers to force their front ends out of the path of movement of the type toward the ejector, and tension springs connected between said guide means and the timing fingers to draw their front ends into the path of forward movement of said type. 50

15. In a type composing machine, a type magazine, an ejector, means including a horizontal disc for carrying type from the magazine to the ejector, a plurality of timing fingers movable over the disc for engagement with the type to permit 55 the presentation of one type at a time by the disc to the ejector, a stationary shaft around which the disc rotates, a sleeve cam secured to, and projecting upwardly from, the disc for rotation around said shaft, a stationary guide means between said sleeve cam and the timing fingers, superimposed sets of lobes formed on the vertical periphery of said sleeve cam, cam rods movable one above the other through said guide means for engagement with respective sets of lobes on 60 the sleeve cam, upturned ends on said fingers for engagement by the cam rods to force said fingers out of the path of forward movement of said type, and tension springs connected between the upturned ends of the timing fingers and the 65 guide means to draw the front ends of the timing fingers into the path of forward movement of said type.

16. In a type composing machine, a type magazine, an ejector, means including a horizontal disc 70

for carrying type from the magazine to the ejector, a guide plate supported above said disc, a plurality of timing fingers having upturned rear ends movable upon said plate, a channel also above said disc through which the type is carried by the disc to the ejector and into which channel the inner ends of said timing fingers project to intercept the movement of the type therethrough, a sleeve cam carried by the disc 5 and formed on its vertical periphery with superimposed sets of lobes, a stationary guide member between said cam and the timing fingers, cam rods movable, one above the other, through said guide member for engagement with respective 10 sets of lobes on the cam to engage the rear upturned ends of the timing fingers to alternately force the latter out of said channel, and tension springs connected between the upturned rear ends of the timing fingers and the guide member to 15 draw the front ends of the timing fingers into said channel when the cam lobes clear the front ends of the cam rods.

17. In a type composing machine, a type magazine, an ejector casing, means including a horizontal disc projecting into said casing for carrying type from the magazine to said casing, a printing segment opposite said casing, and a vertically-disposed rotatable cam in said casing for receiving type from the disc and forcing it to the 20 printing segment.

18. In a type composing machine, a type magazine, an ejector casing, means including a horizontal disc projecting into said casing for carrying type from the magazine to the casing, a printing segment opposite said casing, guide 25 means in said casing leading from the disc to the printing segment, and a vertically-disposed rotatable cam in said casing for receiving type foot 30 first from the disc and forcing it head up along the guide means to the printing segment.

19. In a type composing machine, a type magazine, an ejector casing, means for delivering type from the magazine to the ejector casing, a vertically-disposed cam in said casing, means for 35 rotating said cam, a printing segment opposite 40 said ejector casing, a ledge in the latter upon which type are deposited feet first by the delivery means, a guide track in said casing leading from 45

the ledge to the printing segment, and lobes on said cam adapted to pick up a type from the ledge and place it head up on said track, and thereafter force it along the latter to the printing segment.

20. In a type composing machine, a type magazine, an ejector casing, a printing segment opposite said casing, means for delivering type from the magazine to the ejector casing, two spaced vertically-disposed plates comprising said casing, a horizontal drive shaft projecting axially into said casing, parallel ledges on the inner surfaces of said plates to receive a type foot first from the delivery means, parallel guide rails also on the inner surface of said plates leading from 10 the ledges, over the drive shaft, to the printing segment, a cam secured to said drive shaft for rotation thereby, and radial lobes on said cam adapted to pick up a type from the parallel ledges 15 and place it head up on said rails, with its middle portion between them, and to force said type along said rails to the printing segment when the cam is rotated.

21. In a type composing machine, a type magazine, an ejector casing, a printing segment opposite said casing, means for delivering type from the magazine to the ejector casing, two similar plates comprising said casing, one of said plates being fixed and the other plate being hingedly secured at its top end to the bottom end of the 20 fixed plate, drop bolt means for securing the free ends of said plates together in spaced relation to form the ejector casing, a horizontal drive shaft projecting axially into said casing, parallel ledges on the inner surfaces of said plates to receive a type foot first from the delivery means, parallel guide rails also on the inner surfaces of said plates leading from the ledges, over the drive shaft, to the printing segment, a cam disc secured 25 to said drive shaft for rotation thereby, and radial lobes on the cam disc adapted to pick up a type 30 from the parallel ledges and place it head up on said rails, with its middle grooved portion between them, and to force said type along said rails to the printing segment when the cam disc is rotated.

FRANK H. POEPPELMEIER.
